TRUE M. AVERY, OF GLENS FALLS, NEW YORK, ASSIGNOR TO UNION BAG & PAPER CORPORATION, OF HUDSON FALLS, NEW YORK, A CORPORATION OF NEW JERSEY

TRANSPARENT COVERED TRAY

Application filed March 18, 1931. Serial No. 523,615.

The present invention relates to improvements in receptacles of the class suitable for the packaging and display of articles of different kinds, and more especially confections such as cakes and the like, and the primary object is to provide a transparent covered tray to contain such articles, the tray having sufficient strength or stiffness to maintain its proper form and to support its contents, and having a transparent cover which encloses the contents and renders the same clearly visible for display purposes, the construction of the tray being such that it may be easily and quickly filled and closed.

15 In the accompanying drawing:

Fig. 1 is a perspective view of a transparent covered tray embodying the present invention, the same being shown in filled condition;

20 Fig. 2 is a vertical longitudinal section through the tray in its expanded form, before filling and closing thereof;

Fig. 3 is a bottom plan view, partly broken away, of the tray before filling and closing;

25 Fig. 4 is a top plan view, partly broken away, of the tray before filling and closing;

Fig. 5 represents a transverse section through the tray in its expanded form;

30 Fig. 6 is an end view of the tray, showing one of the end folds for closing it;

Fig. 7 is an end view of the tray showing further folds for closing it;

Fig. 8 is a section taken on the line 8—8 of Fig. 7; and

35 Fig. 9 is a view of an end of the tray showing the same fully folded and closed.

The receptacle or tray provided by the present invention comprises a bottom 1 and a cover 2. The bottom 1 is composed of a strip of cardboard, fibre board or other relatively stiff but flexible or foldable material which is preferably of elongated form as shown, and the cover 2 is composed of thin flexible or foldable transparent sheet material of any suitable kind, such for example as transparent paper or ordinary fibre paper treated in any suitable or well known manner to render it transparent, or "Cellophane" or any of the other well known thin transparent flexible sheet cellulose products ob-

tained from viscose. The strip of material from which the cover 2 is made is wider than the bottom 1, and the longitudinal edges 3 of the cover 2 are extended beneath the longitudinal margin of the bottom 1 and are 55 united thereto, as by longitudinal rows of paste 4. The cover part 2 is folded along the longitudinal lines 5 so that the top of this cover is preferably of the same length and width as the bottom 1, and the sides 6 of the 60 cover part are formed with longitudinally extending plaits 7 so that, before filling, the top of the cover portion may be collapsed flatwise against the upper side of the bottom 1 and during or before filling, the top of the 65 cover portion may be raised, as will be permitted by the unfolding of the plaits, thereby expanding the space between the bottom 1 and the top of the cover to provide a chamber to receive the contents. The bottom 1 and 70 cover 2 are preferably made of the same length, thus enabling the trays to be manufactured on ordinary bag making machines.

The tray may be filled with cakes or other confections or similar articles by lifting the 75 top of the cover, which is permitted by the unfolding of the plaits, the ends of the tray being then open for the reception of the contents. After the tray has been filled, it is closed at its ends by bending the ends of the 80 relatively stiff bottom 1 upwardly along the transverse lines 8 to form the upturned relatively stiff folds 9, one at each end of the tray, after which the sides of the cover 2 at each end thereof are turned inwardly to form 85 folds 10 which are pasted against the respective upturned fold 9 of the bottom, and finally, the extremity 11 of the top of the cover is folded and pasted against the previously made folds 9 and 10, the respective end of 90 the tray being then effectually closed and sealed.

By forming the tray of a relatively stiff bottom and a flexible transparent cover connected to the bottom by longitudinal plaits, 95 the top of the cover may be collapsed flatwise against the bottom before filling, thus economizing space in storing and shipping the trays, and the expansion of the tray, made possible by the plaits, opens both ends there- 100

of so that the contents may be readily introduced endwise into the tray. The folding and closing of the ends of the tray may be accomplished with facility, since the turning 5 up of the ends of the relatively stiff bottom provides relatively stiff backings against which the folds of the sides and top of the cover may be made and pasted.

The transparent covered tray, when filled, 10 possesses many advantages over display packages or receptacles as heretofore used, the relatively stiff bottom maintaining the tray in its proper form although the tray may be of considerable length, and the transparent 15 sides and top of the cover expose the contents of the tray substantially completely.

I claim as my invention:

1. A display tray comprising a bottom composed of a strip of relatively stiff material having its ends bent upwardly, and a cover composed of a strip of transparent material of the same length as said strip of stiff material and having its longitudinal edges secured to the longitudinal edges of 20 the bottom and forming an interior chamber between it and said bottom, and having ends folded against the outer sides of the upwardly bent ends of the bottom.

2. A tray to receive and display articles 30 comprising a flat elongated strip of relatively stiff material forming a bottom, and a cover compound of flexible transparent material of the same length as said strip of stiff material and having its longitudinal edges 35 secured to the longitudinal edges of said bottom strip, said cover having plaits in its sides to provide an expansible space between the cover and the bottom strip and to permit opening of the ends of the cover to admit articles to said space, and the ends of the bottom strip being bendable upwardly into the expanded space between the bottom strip and the cover.

3. A tray to receive and display articles 45 comprising an elongated relatively stiff bottom strip, and a cover composed of flexible transparent material of the same length as said bottom strip and secured along its longitudinal edges to the longitudinal edges of 50 the bottom strip and having longitudinal plaits in its sides for the expansion of the space between the cover and bottom strip and the opening of the ends of the cover for the reception of the articles, the ends of the bottom strip being bendable upwardly into the space between the cover and the bottom strip and the ends of the cover being foldable 55 against the upwardly bent ends of the bottom strip to close the ends of the tray.

60. In testimony whereof I have hereunto set my hand.

TRUE M. AVERY.
